US00D950628S

(12) **United States Design Patent** (10) **Patent No.:** **US D950,628 S**
Au et al. (45) **Date of Patent:** **** May 3, 2022**

(54) **CAMERA**

(71) Applicant: **GoPro, Inc.**, San Mateo, CA (US)

(72) Inventors: **Heman Au**, San Mateo, CA (US); **Huy Phuong Nguyen**, San Mateo, CA (US); **Daniel J. Coster**, San Francisco, CA (US); **John George Muhlenkamp, IV**, Brisbane, CA (US); **Joshua T. Druker**, Redwood City, CA (US)

(73) Assignee: **GoPro, Inc.**, San Mateo, CA (US)

(**) Term: **15 Years**

(21) Appl. No.: **29/760,219**

(22) Filed: **Nov. 30, 2020**

Related U.S. Application Data

(63) Continuation of application No. 29/663,435, filed on Sep. 14, 2018, now Pat. No. Des. 903,740.

(57) **CLAIM**

The ornamental design for a camera, as shown and described.

DESCRIPTION

FIG. 1 is a top, front, and right side perspective view of a camera;

FIG. 2 is a front elevation view thereof;

FIG. 3 is a right side elevation view thereof;

FIG. 4 is a left side elevation view thereof;

FIG. 5 is a top plan view thereof; and,

FIG. 6 is a bottom plan view thereof.

The broken lines depict portions of the camera in which the design is embodied that form no part of the claimed design. Additionally, the dash-dot lines denote the boundary of the claim and form no part of the claimed design.

1 Claim, 5 Drawing Sheets
